UNITED STATES PATENT OFFICE

2,554,007

DISPENSING SPOUT

Albert Brooke and William M. Naumann,
Staten Island, N. Y.

Application December 3, 1947, Serial No. 789,486

1 Claim. (Cl. 222—425)

1

This invention relates to a removable dispensing spout designed for use in connection preferably with containers constructed of heavy cardboard material, and which are now used in packaging granular substances, such as powdered soaps or the like.

The primary object of the invention is to provide a removable dispensing spout of this character which may be readily and easily positioned and securely held by engagement with the walls of the container, adjacent to the discharge opening of the container, the spout having a discharge opening adapted to register with the discharge opening of the container to permit the contents of the container to be poured therefrom.

Another object of the invention is to provide a pouring spout which is so constructed that it provides a chamber into which the granular material being dispensed may be delivered, to the end that measured quantities of the granular material may be dispensed.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawing

Figure 1 is a front elevational view of a pouring spout constructed in accordance with the invention, as positioned over the edge of a box containing granular material, the spout being positioned directly over the pouring opening of the container.

Fig. 2 is a sectional view taken on line 2—2 of Fig. 3.

Fig. 3 is a sectional view taken on line 3—3 of Fig. 1.

Fig. 4 is a fragmental plan view of the pouring spout.

Fig. 5 is a sectional view taken on line 5—5 of Fig. 1.

Referring to the drawing in detail, the pouring spout comprises an elongated body portion 5 which has a forward bulged end portion 6 and outer side walls 7. The portion of the forward end of the body portion indicated at 8, provides the front wall of the spout which fits against the front wall of the container on which the spout is positioned. The outer side walls 7, extend rearwardly from the side edges of this front wall 8, and are formed integral therewith, the outer side

2

walls having their lower edges inclined upwardly towards the rear end of the spout. Formed integral with the body portion 5 and disposed in spaced relation with the outer side walls 7, are inner walls 9 which have their free edges spaced appreciable distances from the side walls 7, while the opposite edges thereof are in such spaced relation with respect to the outer walls 7, that the side walls 10 of the container with which the spout is used, may fit therebetween in close engagement with the spaced walls.

The forward edges of the inner walls 9 are connected by the vertical wall 11, which is also inclined inwardly from the upper edge thereof, to fit over the front wall 12 of the container with which the spout is used. Due to this construction it will be seen that when the spout has been properly positioned over the discharge opening of the container with which the spout is used, the spout will be securely held in position against accidental displacement.

The spout also includes a horizontal wall 13 which is spaced from the top 14 of the spout, the rear ends of the walls 13 and 14 being spaced apart so that they will accommodate the top wall 15 of the container, as shown by Fig. 3 of the drawing.

As clearly shown by Fig. 4 of the drawing, the horizontal wall 13, as well as the walls 11 and 12, are provided with cut out portions that are completely housed by the spout, and through which the granular material from the container is poured for use, the openings referred to, being indicated by reference characters 16 and 17 respectively.

The forward bulged end of the spout is formed with an elongated opening, the edges thereof being grooved as at 18, in which the ribs 19 of the closure 20 operate, there being provided a finger piece 21, whereby the closure 20 may be conveniently moved to its open or closed position.

From the foregoing it will be seen that due to the construction shown and described, we have provided a pouring spout for use in connection with the usual cardboard containers in which granular substances such as soap powders or the like are packaged, the spout affording means whereby the material in the package may be dispensed and protected avoiding waste, due to spilling the contents of the container when pouring, or deterioration when the container is stored away and not in use.

Having thus described the invention, what is claimed is:

A pouring spout for pouring granular material

from containers having discharge openings, comprising a body portion, substantially wide spaced outer and inner flanges depending from the side edges of the body portion, said flanges diverging towards the free edges thereof providing a wedge-shaped space in which the edges of the walls of the discharge opening are held, securing the pouring spout to the container, said pouring spout having a bulged end disposed over the discharge opening of the container providing a compartment in which material is poured from the container, said bulged portion of the pouring spout having a discharge opening spaced below the discharge opening of the container, and a closure controlling the passage of material from the 15 pouring spout.

ALBERT BROOKE.
WILLIAM M. NAUMANN.
